INVENTOR.
William H. Matthews,
BY

Geo. P. Kimmel. ATTORNEY.

UNITED STATES PATENT OFFICE.

WILLIAM H. MATTHEWS, OF NEWBURGH, NEW YORK.

CORNER BLOCK FOR BED SPRINGS.

Application filed April 21, 1925. Serial No. 24,833.

This invention relates to corner blocks for bed springs and has for its primary object the provision, in a manner as hereinafter set forth, of a corner block adapted to receive the end of the side rail of the spring in such a manner that the same may be easily and quickly removed to allow the end rail and the fabric to be rolled up for transportation or storage.

10 A further object of the invention is the provision, in a manner as hereinafter set forth, of a corner block for bed springs adapted to removably hold the end of the side rail of the spring and further having means engaging one end of the side rail, whereby the same may be forced through one block against the block at the opposite end of the side rail to tighten and place under tension the fabric connecting the end rails of the spring.

15 The invention contemplates the provision of a depending bracket member adapted to be secured to one end of the end rail of the bed spring and having extending at right angles therefrom a supporting arm, carrying at the inner and outer end a ring member, through which ring member one end of a tubular side rail is adapted to be extended. The forwardly extending supporting arm 20 has the rear thereof provided with a threaded bore to receive a tightening nut, which nut supports a cup member in such a position that the end of the tubular rail extending through the rings referred to, will be enclosed by the cup and, when the nut referred to is tightened it will draw inwardly toward that ring adjacent the end of the side rail to force the side rail through the rings against the corner block at the opposite end of the spring.

25 A further and final object of this invention is the provision, in a manner as herein-after set forth, of a corner block for bed springs having the above set forth features, and further being of such design that it may be cast in one operation, will be strong and durable, easily set up, and inexpensive to manufacture.

30 The invention will be best understood from a consideration of the following detailed description taken in connection with the accompanying drawings forming part of this specification, with the understanding

that the invention is not confined to any strict conformity with the showing of the drawings, but may be changed and modified so long as such changes and modifications mark no material departure from the salient features of the invention as expressed in the appended claims.

In the drawings:

Figure 1 is a side elevation of a bed spring and the side rail thereof, the fabric and central portion of the rail being broken away, and showing the device embodying this invention as supporting the ends of the side rail.

Figure 2 is a front elevation of the device embodying this invention, showing the end cross rail of the spring connected therewith.

Figure 3 is a central longitudinal sectional view of the device, one end rail, and one end of the side rail of the bed spring being shown in section.

Figure 4 is a rear elevation of the device embodying this invention, one end of an end rail being shown applied thereto.

Figure 5 is a rear elevation of the device removed from the end rail of the bed spring and having the side rail end engaging cup removed therefrom.

Figure 6 is a front elevation of the side rail end engaging cup.

Referring now to the drawings in detail wherein like numerals of reference indicate corresponding parts throughout the several views of the drawings, end rails of a bed spring are indicated at 1 and 2 respectively, these end rails being here shown as of the usual angle iron construction, the end inner opposed horizontal portions thereof forming the top of the frame and the outer vertical depending portion forming the ends of the frame. The usual fabric which normally connects the vertical portions of these end rails 1 and 2, is not shown, as it is well understood how this fabric is connected between these end rails. The end rails 1 and 2 are reinforced by the tubular reinforcing rails 3, which are positioned in the angle of the end rail and secured thereto by means of the bolts 4, certain of the bolts extending vertically therethrough to connect the tubular member with the top portion of the end rail, and certain other of the bolts extending horizontally through the tubular

rail to connect the same with the depending portion of the end rails.

The device embodying this invention comprises a bracket indicated as a whole by the 5 numeral 5 and this bracket comprises a substantially elongated vertical riser 6 having intermediate portion 7, which intermediate portion terminates in the lower end of a second or upper vertical portion 8. This 10 vertical portion as clearly shown in Figure 3 is positioned between the vertical portion of the angled end rail 2 and the reinforcing tubular rail 3 and has the horizontal bolts 4 extended therethrough to secure the same 15 in position. The upper end of this vertical portion 8 is curved inwardly toward the front of the bracket as shown and has at the inner side a forwardly extending finger 9 which is positioned between the reinforcing tubular rail 3 and the top of the end rail, as is also clearly shown in Figure 3. The bracket 5 is of substantial length as 20 shown in Figure 2 and the lower end has a laterally extending ledge 10 to provide the 25 flat foot 11 adapted to stand upon the side rail of the bed frame upon which the spring is placed.

Formed integral with and projecting forwardly at right angles from the inner face 30 of the vertical riser 6, and also at the inner edge of the same, is a horizontal tubular supporting arm 12, the rear portion thereof having a relatively small bore 13 therethrough, which bore is threaded to receive 35 the bolt 14, the purpose for which will be set forth as the description proceeds.

Suspended from the horizontal supporting arm 12 is an inner and an outer like 40 guide ring member 15 and 16, respectively, the inner member 15 being formed at the terminal end of the arm and the outer member 16 is positioned a little inwardly of the rear end of the arm as shown in Figure 3. It will be noted here that the rear portion 45 of the supporting arm 12 opens beneath the angled portion 7 of the bracket and is covered by the end cross rail of the spring.

The side rail 17 of the spring, which is here shown as tubular has its end extended 50 through the depending alined guide members 15 and 16, carried by the bracket at the end of the spring frame. While a tubular side rail has been shown here, it is of course understood that the same may be of 55 any desired cross sectional form, the members 15 and 16 being of the proper form to receive the end of the rail.

Certain of the corner blocks have the outer guide member closed at the back as indicated at 18 in Figure 1 of the drawings, the guide 60 16 then forming a cup to receive the end of the rail 17. When such a corner block is used to suspend one end of the side rail 17, the other corner block has suspended 65 from the bolt 14 a lug 19, which lug is pro-

vided with an elongated opening 20 for the passage of the bolt and further has formed integral therewith and suspends a cap member 21, the open end of which is directed toward and in alinement with the opening 70 in the outer guide 16, and as is clearly shown in Figure 3 is adapted to receive therein the end of the rail 17.

In the construction of a spring making use of the corner blocks of the type described, two of the blocks, one at each corner of one end of the spring frame, are of the type which has the outer guide member closed at its back as indicated at 18 in Figure 1 of the drawings, and the other two 80 members, one at each corner of the other end of the frame and in opposed relation to the first mentioned two members, are of the type which has a pivoted cap 21 suspended at the rear of the guide member 16. With the spring fabric connecting the end rails 1 and 2, the bolts 14 of each of the two brackets at one end of the frame are loosened, and the cap 21 removed from its depending position in alinement with the end guide 16, to uncover the same. The side rails 17 are then projected through the two open guides 15 and 16 and slid therethrough until the forward end of the side rail extends through the inner guide 15 of the other member and seats in the closed ring 16 thereof abutting the back 18. The end rail 2 is then drawn out to tighten the fabric, the cap 21 is swung downwardly and engaged over the projecting end of the side rail whereupon the nut 14 of each corner block beneath the end rail 2, is tightened to draw the cap in against the end rail and force the same through against the back 18 of the ring 16 of the opposing corner block suspended from the end rail 1. In this manner the fabric is effectively tightened and held in stretched position, and the side rails are tightly clamped and immovably held in position as long as the nut 14 retains the lug 19 tightly against the rear end of the tubular supporting arm 12.

From the foregoing description it may be seen that a very novel and improved type of corner block is formed and one which permits the side rails of the spring frame to be easily and quickly removed so that the fabric with the end rails may be rolled to allow for the easy and convenient transportation of the spring without the bother at present experienced in moving bed springs which occupy a large amount of room.

Having thus described my invention what I claim is:

A corner block of the character described, comprising a tubular rail, a cap on the end of the rail and having a perforated upstanding lug, a bracket having guides encircling the rail, a headed screw extending freely through the lug and threaded into the 125 130

bracket for swingingly supporting the cap when the same is removed from the rail, the head of said screw normally holding said lug against said bracket, an offset bearing on the bracket to rest on the side rail of the bed, a riser on the bracket and having seats, and an outer inverted L-shaped and an

inner tubular rail parallel with each other and secured to the riser, said offset rest being formed with bracing webs which extend upwardly of the riser. ¹⁰

In testimony whereof, I affix my signature hereto.

WILLIAM H. MATTHEWS.
